UNITED STATES PATENT OFFICE.

ROBERT PAUL GELLRICH, OF HAMBURG, GERMANY.

TUG-GEAR.

1,115,807.

Specification of Letters Patent.

Patented Nov. 3, 1914.

Application filed June 4, 1914. Serial No. 842,839.

To all whom it may concern:

Be it known that I, ROBERT PAUL GELLRICH, a subject of the German Emperor, and residing at 65 Bullerdeich, Hamburg 35, Germany, master smith, have invented certain new and useful Improvements in Tug-Gears, of which the following is a statement.

The hitherto known tugging gears for automatically slipping the hawser have the great disadvantage, that their mechanism is much too complicated, and can be brought into operative position only with the aid of several persons, so that inconvenient delays are caused, which may even lead to trouble, as it will easily occur that parts of the complicated tugging gear hitch or catch and do not close up together. These tugging gears, furthermore, have the disadvantage of not being able to prevent the tug-boat from capsizing.

The object of the present invention is to provide a tugging gear for automatically slipping the hawser and preventing the capsizing of the tug-boat if the hawser should sheer to one side. This tugging gear will not only avoid the disadvantages of the gears heretofore known, but also affords considerable advantages over the latter, in particular by the fact that also when the hawser is slipping automatically, a capsizing of the boat is prevented.

Another feature of the present invention consists in its greatly reducing the purchase price.

In the accompanying drawing the present invention is exemplified.

Figure 1 is a side elevation of the tugging gear fitted to a tug-boat. Fig. 2 is the tug-gear on an enlarged scale in closed position. Fig. 3 is the tug-gear according to Fig. 2, in opened position. Fig. 4 is a top view of the tug-gear fitted to a tug-boat, with the hawser sheered out to the one side. Fig. 5 is a section on the line A—B in Fig. 4. Fig. 6 is the same section as in Fig. 5, but showing the tug-boat heaving over the side.

The tug-gear according to the present invention consists of the tug-gear proper having the shape of tongs, and the two suitable bent guide supports *r* and *t*, which are fitted in a suitable manner to the body of the boat and serve as guides for the tug-gear. The tug-gear is secured to the support *r* by means of a strap *p* which is hinged by means of a bolt *q* to the lower leg *a*, while the support *t*

is disposed between the two legs *a* and *b*, and thereby prevents the whole gear from dropping. To the front end of the leg *a* is pivoted on a pin *n* a finger *l*, over which the ring *v* of the hawser is placed, and which is so arranged that its tongue *z* engages in the bore *o* in the leg *b*, thus forming an eye-shaped mouth *u*, from which the hawser ring cannot slip unintendedly. The finger *l* is locked in position by means of a toggle joint *s*, the upper member of which is made in form of a lever bar *h*. This toggle joint is pivoted to the legs *a* and *b* by means of the pins *d* and *e* respectively. When the toggle lever is stretched, the tongue *z* of the finger *l* will be held in the bore *o* of the leg *b*, so that the finger cannot be opened. When the toggle joint *s* is folded by means of the lever *h*, the members of said toggle lever fold together and the upper arm *b* is lowered, so that the mouth *u* is opened; the bore *o* then disengages from the tongue *z* of the finger *l* and the latter falls over under the pull of the hawser *w*, whereby the latter is automatically slipped. For the purpose of allowing of slipping the hawser also from the wheel, the toggle lever *s* is coupled to a rope *x*, and a short pull on this rope will be sufficient to fold the toggle and slip the hawser. When in stretched position, the toggle lever *s* engages in the forked lug *i* of the leg *b*, and bears against a stop *k*. If the hawser should sheer to one side, and the boat also heave over to this side, the support *t* will bear on the leg *a* of the tug-gear, which is held in position by the strain on the hawser, and is supported by this leg so that the boat will not heave over any farther and its capsizing is prevented.

By the arrangement of this simple tug-gear it is, on the one hand, possible to automatically slip the hawser, and on the other hand, a capsizing of the tug-boat is prevented. Lastly its cheap manufacture will reduce the purchase price.

I claim:

1. Tug-gear for automatically slipping the hawser and for preventing the capsizing of the tug-boat if the hawser should sheer to one side, comprising a tug-gear proper composed of two legs forming a shear, the lower of said legs having a finger adapted to receive the ring of the hawser and pivoted to said lower leg, said finger engaging with a tongue in a corresponding bore in the upper leg of the shear, a toggle-lever, adapt-

ed to hold said finger in engagement with said bore, when in stretched position, the one member of said toggle lever having the form of a lever adapted to fold said toggle lever and thereby also close the rearward ends of the legs and disengage said finger from said bore.

2. Tug-gear for automatically slipping the hawser and for preventing the capsizing 10 of the tug-boat, if the hawser should sheer to one side, comprising a tug-gear proper composed of two legs forming a shear, the lower of said legs having a finger adapted to receive the ring of the hawser and pivoted to said lower leg, said finger engaging with a tongue in a corresponding bore in the upper leg of the shear, a toggle-lever, adapt-

ed to hold said finger in engagement with said bore, when in stretched position, the one member of said toggle lever having the form 20 of a lever adapted to fold said toggle lever and thereby also close the rearward ends of the legs and disengage said finger from said bore, a guide support fitted to the body of the ship and adapted to bear on the tug-gear under the strain of the hawser and thereby prevent the capsizing of the boat.

In testimony whereof I have hereunto set my signature in the presence of two subscribing witnesses.

ROBERT PAUL GELLRICH.
